UNITED STATES PATENT OFFICE.

JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

DOOR-OPERATING MECHANISM.

1,149,219.

Specification of Letters Patent. Patented Aug. 10, 1915.

Application filed March 14, 1911. Serial No. 614,489.

To all whom it may concern:

Be it known that I, JOHN M. ROHLFING, residing at St. Louis, Missouri, and being a citizen of the United States, have invented 5 certain new and useful Improvements in Door-Operating Mechanism, of which the following is a full, clear, and exact description, such as will enable others skilled in the art to which it appertains to make and to 10 use the same, reference being had to the accompanying drawings, which illustrate the preferred form of the invention, though it is to be understood that the invention is not limited to the exact details of construction 15 shown and described, as it is obvious that various modifications thereof will occur to persons skilled in the art.

In said drawings: Figure 1 is a longitudinal horizontal sectional view through the hopper of a car and illustrates in top plan view my improved doors applied to the discharge opening thereof. Fig. 2 is an end elevation of a portion of the hopper, the view being taken on the plane indicated by 25 line 2—2 of Fig. 1 and parts of the car structure being illustrated in section. The doors are here shown by full lines as being fully closed and locked, and by heavy dotted lines as being partly closed. Fig. 3 is a view 30 similar to that shown in Fig. 2, but the parts being shown diagrammatically. In this view the doors are represented in process of being opened beyond the position illustrated in Fig. 2. Fig. 4 is a vertical transverse section taken on the plane indicated by line 35 4—4 of Fig. 1. Fig. 5 is a top plan view of the end portion of one of the double doors showing the operating mechanism applied thereto and illustrates, in section, the supports 40 for said mechanism pendant from the car body. Fig. 6 is a vertical sectional view taken on the plane indicated by line 6—6 of Fig. 5, the parts being shown on an enlarged scale. Fig. 7 is a vertical sectional 45 view taken on the plane indicated by line 7—7 of Fig. 5, the parts being seen on a scale corresponding with that shown in Fig. 6. Fig. 8 is a detail perspective view of the detachable operating lever. Fig. 9 is a fragmental side view taken on the line 9—9 of Fig. 5 wherein the door operating mechanism has been removed to more clearly show the locking mechanism.

The object of this invention is to provide

a car of the hopper bottom type which shall 55 have a maximum area of discharge-door opening in proportion to the size of the car and to provide a door, or more correctly, a pair of two part or compound doors, which may be readily operated by an operator, at 60 the side of the car for closing said door opening.

A further object is to provide an operating mechanism for these doors which will 65 permit of practically simultaneous opening and closing of each pair of doors, the mechanism being arranged and connected so as to be capable of operation from either side or end of the car.

A further object is to so proportion the 70 doors and to so position their means of operation that the clearance space between the bottom of the car and the roadbed may be reduced considerably beyond that which would be required were a pair of single 75 doors employed to control a discharge opening of the given size.

The doors are arranged preferably longitudinally of the car and are four in number, 80 a pair, or two doors, upon each side of the center line of said car. The operating mechanism for the doors is composed of parts briefly stated as follows: Two operating shafts 1—1 disposed one upon each side of the hopper and extending from end to end 85 thereof; four gears as at 2 fixed one to each end of each shaft 1; four door operating members as 3—3 shiftable transversely of the car and disposed two at each end of said hopper, arranged each to engage and to be 90 shifted by the adjacent gear 2 on the respective operating shafts 1 and each extending from the said gear inwardly toward the median line of the car. Four segmental pinions as 4 operatively engage the inner end of 95 each of the shiftable door operating members 3; two longitudinally shiftable double-faced rack-bars as at 5 are arranged along the median line of the car at opposite ends of the doors, and each of said rack-bars are 100 operatively engaged by the adjacent pair of segmental gears 4, said rack-bars serving as a positive support and lock for the inner ends of the doors when the same are closed; and finally said door operating mechanism 105 comprising means connected with each of the doors and arranged to be engaged by the transversely slidable operating members 3

for positively controlling the movements of the doors.

It will become apparent from the following detail description of the parts, and from the description of the operation thereof, that the final closing action of the doors is accompanied by an outward movement of the transversely shiftable door operating members 3 and that, through the medium of the 10 segmental gears 4 connected to said shiftable members, such movement of the members 3 will produce a movement of the rack-bars 5 toward each other or to positions beneath the adjacent edges of the respective doors. 15 It will also become apparent that the various steps of the operation are so timed that the inner or locking ends of the rack-bars will not be caused to project into position beneath the edges of the doors until after 20 the doors are fully closed, but when so projected said locking bars constitute a positive and independent support for said doors.

The operating mechanism for the doors is duplicated at each end thereof and said 25 mechanism is also duplicated upon each side of the median line of the car. The operating mechanism is so connected that each of the four units, of which it is obviously composed, will be subjected to simultaneous operation when any one of the units is operated. It is therefore, only necessary to illustrate and describe in detail one of these units; that is, that portion of the operating mechanism which lies at one end of the 30 doors and upon one side of the said median line.

The body of the car is preferably of metal construction, comprising side plate girders, or supporting members which are adapted 40 to carry the load. These girders are shown only in fragment in Figs. 1, 2 and 4. The numeral 6 indicates the bottom or tension angle of one of said girders and 7 the plate thereof. To these parts are secured the 45 usual vertical stiffening posts 8. Fixed to the side girders and depending obliquely therefrom are the side hopper plates 9—9.

The end plates as 10 of the hopper are secured at their opposite edges to the adjacent 50 side girders and are extended downwardly to the bottom edge of the side hopper plates 9 to the adjacent edges of which they are also secured. A discharge-door opening of unusual proportionate size is formed by the 55 lower edges of the side and end hopper plates.

Hinged at the lower edge of each of the side hopper plates 9, preferably in hinge-members as at 11 secured to a suitable horizontal stiffening angle as 12 along the bottom edge of said plate, is a door 13 extending, in width, from the lower edge of the plate 9 to a point slightly more than midway between the bottom edge of the said 60 plate and the median line of the car, and

in length from the bottom edge of one end plate 10 to the bottom edge of the other end plate 10.

Hinged to the free end of door 13 is a second door 14. The door 14 is of equal 70 length with the door 13 and is of width sufficient to close the space between the free edge of said door 13 and the median line of the car. Other doors 13 and 14, duplicates 75 of those just described, are disposed upon the opposite side of the median line so as to close the discharge-opening space upon the other side of said median line. Each of the doors 13 and 14 is composed of a top plate 15 stiffened along its inner and outer 80 edge by longitudinally disposed Z-sections 16, the web of the Z-sections being arranged, in each instance, to depend from the bottom face of the plate 15 at points spaced from the adjacent edges thereof.

The upper flanges of the Z-sections are disposed to lie flat against the bottom faces of the plates 15 and to extend practically to the edges thereof. The lower oppositely disposed flanges are arranged to project inwardly toward the median line of each of the respective doors.

The hinge-members 17 attached to, and supporting, each of the doors 13 are fixed to the outer Z-sections 16 and are arranged 95 so that the axis of the hinge shall be above the face of the door, thereby insuring a full opening of the door for affording an increased outlet. The said hinge members extend into pivotal engagement with the hinge-members 11 supported at the lower edge of the hopper side plates 9. The hinge members 18 of the doors 14 are secured to the Z-sections 16 adjacent the free edges of the doors 13 and extend into pivotal engagement 100 with similar members 19 secured to the adjacent edges of said doors 13.

In closed position the free edges of the doors 13, and hence the adjacent edges of the doors 14, are supported upon suitable stationary supporting lugs 20 formed upon arms 21 depending from the adjacent edges of the end plates 10. Each of the arms 21 is reinforced in its connection to said end plate 10 by rivet connection to a stiffening 115 member 22 fixed to the under side of said plate. The supporting lugs 20 are preferably cylindrical in form and are arranged so that the center thereof shall lie in the same straight line as the axis of the door 120 hinge when the same is closed.

Fixed to the under side of each end of the door 13 is a casting 23. This casting is disposed between the depending webs of the longitudinal stiffening Z-sections 16. The 125 casting is formed with an upper horizontal plate 24 extending from the web of one of the Z-sections 16 to the web of the other Z-section and secured by rivets to the top plate 15 for stiffening said plate at its end. 130

The casting is formed also with depending end flanges 25 and 26 lying flat against the adjacent faces of the webs of the Z-sections. A flange as 27 depends from the outer edge 5 of the horizontal plate 24 to a point somewhat below the lower flanges of the Z-sections 16. This latter flange extends from the depending flange 26 to and past the depending flange 25 and the adjacent end of 10 the Z-section 16. That portion of the flange 27 which extends beyond the end of the Z-section 16 and below the same, is arranged to support, at a point somewhat below the upper surface of the door, a roller 28, more 15 clearly shown in Fig. 5 which roller is designed to project outwardly from said flange and to be engaged by a depending lug 29 formed upon the under surface of the outer end of the transversely slideable door operating member 3 for swinging said door about its pivot.

Fixed to the under side of each end of the door 14 is a casting 30. This casting is disposed between the depending webs of the 25 stiffening Z-sections 16, secured to the bottom face of said door. The casting 30 is formed with an upper horizontal plate 31 extending from the web of one of the Z-sections 16 to the other of the Z-sections, and 30 is secured by rivets to the top plate 15 for stiffening said plate at its opposite ends. The casting 30 is also formed with depending end flanges 32 and 33 lying flat against the adjacent faces of the webs of the Z-sections. 35 A flange as 34 depends from the outer edge of the horizontal plate 31 downwardly to the bottom edges of the flanges 32 and 33 and serves to connect said flange 32 with said flange 33. 40 Extending from the bottom edge of the flange 34 to a point somewhat below the lower surface of the Z-sections 16 is an arm 35, at the lower end of which is pivotally mounted a spring latch 36 adapted to engage 45 a coöperating lug 37 projecting outwardly from the face of the depending flange 27 of the casting 23 on the door 13.

Formed upon the latch 36 and extending 50 radially from the pivot thereof in the arm 35 is an arm 38 adapted to engage a depending lug 39, adjustably mounted upon the support 21, for a purpose which will be hereinafter described. The arm 35 on the door 14 is formed with a limiting stop 40 adapted 55 to be engaged by a similar stop 41 formed upon the latch 36 for maintaining the proper relative position of said latch with the door 14. A suitable pocket 42 is formed in the arm 35 for receiving a spring 43 adapted to 60 maintain engagement between the stops 40 and 41.

Formed integral with the casting 30 on the end of door 14 is an arm 44 which is disposed parallel with and is off-set so as to 65 be partly spaced from the end of the door.

The arm 44 extends to a point slightly beyond the vertical plane of the pivot line of said door with the door 13 and above the horizontal plane of the said pivot line and is adapted to support at its free end an outwardly extending anti-friction roller 45 designed to be engaged by a portion of the member 3, for a purpose hereinafter described. 70

The lower face of the arm 44 is recessed 75 as at 46 and said recess is adapted to rest, when the doors are closed, upon the upper surface of the stationary support 20 fixed to the hopper plate 10.

Arranged upon the opposite sides of the 80 hopper, below the side girders, and supported in bearings 47 fixed to the tension angles 6 of said girders and to the adjacent hopper plates 9, are the operating shafts 1, to the ends of which the gears 2 are fixed. Each 85 of the gears 2 is adapted to engage the teeth of a rack 48 formed upon the upper side of the outer end of the adjacent member 3 for moving said member for operating the doors. Fixed to each of the shafts at a point 90 intermediate the length thereof, and convenient of access to an operator, is a lever socket 49 adapted to receive the shouldered end 50 of the detachable operating lever 51 for rotating said shaft. 95

The operation of the doors requires that the shafts 1 be partially rotated in unison first in one direction and then in the other. This fact renders it necessary that there be provided a pair of sockets 49 disposed in 100 opposite relation so that the end of the operating lever may be inserted into either of said sockets, according to the direction into which it is desired to rotate the shaft at a given time. These sockets may be formed in a single casting, as illustrated, or may be formed into two separate castings, if desired. 105

The door operating member 3 is transversely slidably supported by a bracket 52 110 depending from the end plate of the hopper. This bracket is formed of a pair of vertically disposed plates, one upon each side of the member 3. An anti-friction roller 53 is mounted between the inner faces of these plates near the lower edges thereof and the member 3 is adapted to rest slidably upon this roller. A roller 54, similar to the roller 53, is fitted above the member 3 115 opposite the roller 53, and is designed to prevent an upward displacement of said member 3. 120

Secured to the end plate 10, adjacent the inner end of member 3 and above said member, is a grooved guide plate 55 adapted to 125 slidably receive a guiding-feather 56 formed upon the upper surface of the member 3 adjacent the inner end thereof.

Spaced from the inner end of the member 3 and formed in the under surface thereof is 130

a recess 57. The recess 57 is formed in such manner as to provide an outwardly facing vertical shoulder 58 which, when the doors are locked, will assume a position slightly 5 outside the vertical longitudinal plane of the center line of the roller 45 on the door 14, and so as to bring a flat under surface as 59 of said member 3 into position above said roller, and from said roller to said 10 shoulder, which flat under surface is adapted to engage the upper surface of the roller, for maintaining the door 14 in its closed position pending the insertion of the end of the bar 5 beneath the outer edge thereof. 15 At the extreme inner end of the member 3 a head 60 is formed provided with a transversely horizontally disposed slot 61.

Horizontally, pivotally supported at the lower end of a suitable bracket as 62, dependent from the end structure of the car, is one of the segmental pinions 4, the teeth of which are adapted to engage rack teeth formed in the vertical sides of the locking bar 5. A radially extending arm 63 is 25 formed upon the pinion 4 and projects into sliding engagement with the slot 61. The bars 5 at opposite ends of the hopper are supported by heavy depending brackets 64 fixed to adjacent reinforcing members 65 of 30 the hopper end plates.

The operation of the parts for opening the door is as follows: Assuming the doors to be locked, the parts of the operating mechanism are in position as shown by full 35 lines in Fig. 2, the door operating members 3, are in their outermost position and the flat undersurface 59 of these members rests upon the roller 45, which projects from the offset operating lever arm 44 of the door 40 14 (shown in top view in Fig. 5 and in side view in Fig. 9) and the under concave portion 46 (shown in Figs. 3 and 9) of the said offset lever arm rests upon the supporting lug 20 which is stationary and is secured 45 to the car body plates 10 by a brace 21; in this position, referring particularly to Figs. 2, 5 and 9, it will be seen that the offset operating arm 44 is in its horizontal position and that the door 14 owing to the 50 projection of the said offset lever arm beyond the hinged axis of the door 14 would hold the said door in closed position on account of the pressure of the flat undersurface 59 of the door operating member 3 bearing upon the projecting roller 45 and the said door 14 would also be held in closed 55 position by the lock bar 5. Rotation of the shaft 1, in a contra-clockwise direction (Figs. 2 and 5) will, through the gear 2, move the rack 48, which rack is integral with the 60 slideable door operating member 3, and move the said member inward toward the center of the car. This operating member 3 through a sliding pivot connection with the extension 63 of the segment 4 operates to

withdraw the central locking bar 5, which operation is accomplished very expeditiously owing to the length of the radial extension 63 and the sliding pivot connection with the operating bar 3. In fact this action is so timed that the central locking bar 5 is moved from locking position before the roller 45 can enter the recess 57 and the door 14 cannot drop until the offset operating lever arm 44 rotates concentrically with the hinged axis of the door, which can only occur when the roller 45 enters the recess 57. This permits the door to swing downward by gravity rotating on its own hinged axis restrained only by the offset lever arm 44 as the roller 45 presses against the shoulder 58 of the door operating member 3. As the door operating member 3 moves farther inward toward the center of the car the shoulder 70 of the recess 57 forces the roller 45 of the offset operating lever arm 44 to move farther around on its hinged axis until the latch 36 of the door 14 engages the lug 37 on the door 13. The door 13 is held in closed position until the offset-operating-lever-arm-roller 45, having caused the two doors to latch together, reaches the lower end of the shoulder 70 of the operating member 3 where the said shoulder is inclined or cut 95 away outwardly, the door 13 will drop, the roller 28 carried on the outside of the said door 13 (Figs. 2, 3 and 5) and abutting against the lug 29 of the slideable door operating member 3 will carry the slideable 100 door operating member to first position on account of the weight of the doors pressing against said lug 29.

To close and lock the door: the shaft 1 is 105 rotated as before, in a contra-clockwise direction (Fig. 3). The lug 29 engaging the roller 28 will swing the door 13 upwardly. As the position shown by full lines in said figure is reached, the arm 38 of the latch 36 will engage the lower end of the adjustable lug 39 and the farther upward movement of the door 13 will cause the arm to be depressed so that the latch 36 will be released from the lug 37 and bring the recess 46 in contact with the fixed supporting lug 20 115 whereupon the door 14 will fall by gravity to a perpendicular position and during such operation the weight of the doors will rotate the offset operating lever arm 44, and the roller 45 carried thereby will bear 120 against the shoulders 70 of the recess 57 and cause the offset operating lever arm which operates concentric with the door hinges to slide over or around the fixed supporting lug 20, the axis of which lies in the 125 same straight line as the axis of the door hinges, beyond the center of the said supporting lug 20 hooking thereon and holding the door 13 in uppermost or closed position, and simultaneously with the swing of the 130

said operating lever arm 44 around the lug 20, which occurs too rapidly to permit the door 13 to drop, the operating member 3 is forced outward by the roller 45 of the operating lever arm 44 which said roller operates against the shoulder 70 of the recess 57 of the operating member 3 and thereby places the said roller 45 in position to be engaged by the shoulder 58 of said recess 57 when said shoulder is moved outwardly by a clockwise rotation of the shaft 1. As the roller 45 is forced before the said shoulder 58 the arm 44 will be caused to move concentrically above the supporting lug 20 and to assume the position illustrated by full lines in Figs. 2 and 9 with the concaved under face thereof resting solidly upon the upper face of the supporting lug 20.

As the member 3 is moved to its outermost position; that is, the position in which it is illustrated in full lines (Fig. 2), and while the flat under surface 59 of the member 3 is moving above the roller 45 and thus maintaining said door in its closed position, the locking-bar 5 will be thrust beneath the free edge of the door 14 by the rotation of the pinion 4 and the closing and locking operation will be complete.

Having thus described my invention, what I claim as new and desire to secure by Letters Patent is:—

1. A pair of gravitating compound doors, operating mechanism therefor, and movable means actuated by said operating mechanism and engaging with and locking said doors.

2. A pair of compound doors, operating mechanism therefor, and movable means actuated by the door operating mechanism and engaging with the inner edges of said compound doors and supporting the same in closed position.

3. A pair of compound doors, operating mechanism therefor, a latch engaging with and supporting the inner edge of one of said doors in its open position, means operated by the door for releasing said latch, and operating mechanism and releasing mechanism carried by said door operating mechanism for releasing the other of said compound doors.

4. A door pivoted along one of its edges, a second door pivoted to the free edge of the first-named door, means for folding said second door upon the first-named door, and means carried by and engaging between said doors for maintaining said folded position.

5. A door pivoted along one of its edges, a second door pivoted to the free edge of the first-named door, means for folding the second door upon the first-named door, means permitting opening of the two doors together after such folding, and means carried by and engaging between said doors for maintaining said folded position.

6. A door pivoted along one of its edges, a second door pivoted to the free edge of the first-named door, operating means for said doors, means for folding the second door upon the first-named door, and a latch 70 adapted to engage and maintain the doors in folded position.

7. A pair of compound doors the doors of each pair being pivotally connected together, means for moving one of said doors upon 75 its pivot and means for interlocking one of said doors with the other door before the latter reaches its full open position.

8. A pair of compound doors the doors of each pair being pivotally connected together, 80 means for moving one of said doors upon its pivot, means for interlocking one of said doors with the other door before the latter reaches its full open position, and holding and supporting mechanism for said doors 85 controlled by the operating mechanism.

9. A pair of compound gravitating doors, operating and locking mechanism therefor and for folding one door upon the other, and means on opposite sides of the car for 90 actuating the door operating mechanism.

10. A door pivoted along one of its edges, means for swinging said door into a closed position, an offset arm, a stationary support therefor, and means whereby said arm is released by the swinging of the door. 95

11. A door pivoted along one of its edges, means for swinging said door into a closed position, an offset arm, a stationary support therefor, and means whereby said arm is 100 released by the swinging of the door, said arm constituting a supporting lug for said door.

12. A door pivoted along one of its edges, mechanism engaging the door and closing 105 the same, a second door pivotally connected to the free edge of said first-named door, and offset lever arms carried by the second door and adapted to maintain the first door in closed position. 110

13. A door pivoted along one of its edges, mechanism engaging said door to close the same, a second door pivotally connected to the free edge of said first-named door, a lever carried by the second door and adapted to maintain the first door in position, and a locking bar actuated by the door operating mechanism to engage beneath the free edge of the second-named door to lock it in closed position. 115

14. In a door operating device for cars, a door pivoted along one of its edges, a support for the free edge of said door attached to the car, means for swinging said door to a closed position adjacent said support, a second door and means carried by said second door adapted to engage said support for maintaining said first door in a closed position. 125

15. In a door operating device, a door piv- 130

5 oted along one of its edges, a second door pivotally connected to the free edge of said first door, a slidably mounted door operating member, means for sliding said operating member, means formed upon said operating member adapted to close one of said doors, means formed upon said operating member adapted to close said second door, means carried by said second door for locking said first door and means operated by said operating member adapted to locking said second door.

10 16. In a door operating device, a door pivoted along one of its edges, a second door 15 pivotally connected to the free edge of said first door, a slidably mounted door operating member, means for sliding said operating member in two directions, means formed

upon said operating member adapted to close one of said doors when said operating member is moved in one direction and means formed upon said operating member adapted to close the other of said doors when said operating member is moved in the other direction.

17. In a dumping car, an outer door and an inner door, and means permitting the inner door to open and interlock with the outer door before the outer door reaches its full open position.

In witness whereof I have hereunto set my hand in the presence of two witnesses.

JOHN M. ROHLFING.
